YARN PACKAGE SUPPORT

James Elwood Johnson, Cleveland, Ohio, assignor
to Industrial Rayon Corporation, Cleveland,
Ohio, a corporation of Delaware

Application March 2, 1950, Serial No. 147,255

3 Claims. (Cl. 242—130)

1

This invention relates to a yarn package support and securing means, and more particularly to a yarn package support employed in a creel that is adapted to readily secure and hold a yarn package wound on a core or spool against displacement.

Yarn packages that are wound on hollow cores in the form of cylinders or cones or spools are generally supported on stationary shafts or arbors held in brackets that are attached to vertical supports of creels and secured thereon by an internal or external locking means. The yarn packages are secured in position so as to prevent a malformed package from being pulled off during a yarn withdrawing operation. Low denier yarn will readily break during a creeling operation due to some fault in its initial winding while yarn packages having yarn of about eleven hundred denier and over will not break as easily. A malformed package of heavy denier yarn can be pulled off its support unless it is securely held because of the greater tensile strength of such yarn, and such a yarn package which may weigh about four pounds and more, can damage adjacent equipment as well as itself when it is suddenly pulled off its support.

Various locking devices have been proposed for securing a yarn package to its supporting shaft or arbor. While some locking devices are satisfactory their use is generally limited to small packages; or they are not adaptable to different package shapes; or that they are not easily operable so as to readily secure or release a yarn package; or that the locking and securing devices interfere with the withdrawing yarn. This invention provides for a yarn package support and securing means in a creel that is adapted to support and to securely hold a package wound on a core having the shape of a cone or a cylinder.

The yarn package support of this invention secures a core against displacement by frictionally holding the core by its inner surface. Generally, the core securing means is an axially compressible and transversely expandable sleeve made of a resilient material which, upon compression, will expand in a transverse direction against the interior wall of the core. The core securing and holding means tends to securely grasp the inner core surface since the material of which it is composed flows so as to conform to the shape of the core. Further, whether the core is a cone or a spool, if the size of either falls within the expanding limits of the expandable sleeve, then each is adapted to be securely held. Another advantage is that a core when locked into position

2

is substantially well centered without, generally, the need of another centering device on the arbor.

5 A means for compressing the core holding and securing sleeve is advantageously positioned on the exterior of a mounting bracket and it is operable therethrough. The compressing means comprises a cam to which the yarn package supporting shaft or arbor is connected at one end, and when the arbor is drawn against the bracket the resilient sleeve is axially compressed and transversely expanded. The yarn package support is also adapted to be adjusted so as to accommodate different length packages by a change in the position of the core holding and expanding sleeve on the arbor.

This invention will be explained in greater detail in the following specification and in the accompanying drawing, where:

20 Figure 1 represents in elevation a pair of yarn packages supported in a creel;

Figure 2 is a plan view of Figure 1 showing locked and unlocked positions of the core holding and securing means of this invention;

25 Figure 3 represents, in elevation, the yarn package holding and securing means;

Figure 4, taken across lines 4—4 of Figure 3, represents the adjustable sleeve portion of the yarn package arbor support which permits a different positioning of the expandable sleeve on the arbor.

Figure 5 is a section of Figure 3 taken across lines 5—5;

30 Figure 6 is a partially cut-away view showing a partial large cone-shaped yarn package, and a smaller cone-shaped yarn package secured and supported against displacement on the same arbor; and

35 Figures 7 and 8 represent partially cut-away views of cylindrical yarn packages, and the package supporting and securing means in adjusted position.

In the drawing yarn packages 10 in the form of cones are supported on vertical posts 14 of a creel.

40 The cones 10 are positioned about longitudinally movable stub shafts or arbors 12 supported in the creel support or brackets 13. A creel may have several hundred and more packages. The yarn from the cones 10 is withdrawn over the free end 50 of the packages through various guiding and tension devices (not shown) generally onto a warper creel or to a loom. Further, since yarns are generally axially withdrawn and if a package is imperfectly wound, it is subject to being pulled off 55 when the yarn is of heavier denier. A suddenly

pulled package endangers adjacent equipment, the remaining yarn on the package, and it may also endanger the operator of the creel. Locks or package securing means that are easily operable and out-of-the-way, of a simple construction, are essential.

The package on the right of Figures 1 or 2 is shown as being locked to the supporting arbor 12 by means of the cam 16 which is eccentrically pivoted about a pivot 18. The cam 16 is operable by the handle 17 and since it is secured to the arbor 12, it is adapted to longitudinally or axially move the arbor in the bracket 13 when caused to rotate against the stationary cam face or reaction face 20 of the mounting bracket 13. Thus, when the handle 17 is in the downward position the arbor is drawn toward the bracket 13 and the yarn package 10 becomes locked to the arbor, and when the handle 17 is in an upward position the yarn package 10 then is in a released position.

As shown in Figure 3 the arbor 12 extends through the bracket 13 and it has about it abutting sleeve sections 21 and 22. The sleeve section 21, as shown in Figure 4, is removable for adjustment purposes, while sleeve section 22 is fully cylindrical and it is adapted to be slidably located about the arbor. Ahead of sleeve section 22 is a thrust washer 23, a compression spring 24, a washer 26, then the compressible and transversely expansible sleeve member 25. The member 25, in turn, is compressed by the thrust collar 27 and a spring washer 29 which rest in a groove at the end of the arbor or shaft 12. Thus, as shown in the dotted lines of Figure 3, when the handle 17 of the cam 18 is swung downwardly, the shaft 12 is pulled rearwardly through the supporting bracket 13 to effect a compression and an expansion of the resilient sleeve 25 against the spring 24 and the section sleeves 22 and 21 which are fixed in position and which abut the bracket 13.

As shown by dotted lines in Figures 3 and 5, the expansible sleeve 25, which can be of resilient material such as rubber and the like, upon compression tends to expand in a transverse plane, and upon release to its previous form. Upon compression the sleeve 25 increases in diameter and thus it frictionally locks itself to an inner surrounding core surface. The expansion of the sleeve 25 against and about the interior of the core firmly secure the core to its arbor. The expansion, and the ability of a rubber-like material to flow is generally substantial so that at one position it can accommodate a cone-like package as well as cylindrical package having substantially similar diameters.

Further resiliency to the core locking means is added by the use of the compression spring 24 which prevents injury to the interior of a core by absorbing any excess expansion in the direction of the transverse plane over the amount that is necessary for an adequate holding of a core. The compression spring 24 also tends to maintain at all times a substantially constant pressure against a core by the expandable locking member 25 which, as stated hereinbefore, conforms to the contour or shape against which it bears. The expansible member 25, in addition to securely holding a core of a yarn package, also tends to center the yarn package about the arbor 12.

The same arbor can be used, if desired, for various sized packages. As shown in Figure 6 the arbor 12 is adapted to hold and secure a small cone or a larger cone. The arbor, of course, must

be of a length so as to accommodate both sizes. The larger of the two will be secured more forwardly by its cone than the smaller; each, however, is just as securely held, and substantially firmly centered.

Should smaller cones be used, or cylindrical yarn packages having cores of different diameters, or packages whose length may be such that it is desirable to support them at substantially their mid-point the resilient sleeve member 25 can be readily moved from its forward position as shown in Figure 3 to somewhere nearer the supporting bracket 13. The removable sleeve section 21 is taken from about the arbor 12 by withdrawing the clamping section 30, then moving the sleeve section 22 toward the bracket 13. The removed section 21 is then placed ahead of the locking washer 29. The expanding member 25 will, then, upon an actuation of the cam 18 lock and securely hold a core at some desired position within a core other than at the end, as shown in Figures 7 and 8.

Since there is a tendency for the expanding sleeve 25 to pull the core back slightly, it in instances is advantageous to provide a backing plate or washer 31 that is larger than a core diameter. The backing washer 31 serves to better center the package about the arbor where it is supported only by the expansible sleeve 25.

A supporting arbor of the type herein described is readily adjustable for various types of packages, and it is long-lasting since overexpansion of the resilient member 25 is always absorbed by the compression spring 24. The compression spring regulates and keeps consistent the compression of the resilient member 25 against a core interior. Further, the parts comprising the arbor need not be manufactured to close tolerances since the spring 24 can absorb any differences in the length of such parts. Tension in the spring can be readily varied by the use of additional washers. As shown the arbor is readily adjustable by the simple expedient of removing a sleeve section from the one side of the expansible member 25 to the other. The support thus becomes readily adapted for different types of packages. If desired, a threaded nut can replace the thrust collar 27 on the forward end of the shaft 12 so that in lieu of using the removable sleeve 21 the nut could be threaded into thrust position. The shaft 12 would, of course, have to be threaded for at least the length of the sleeve 21 which would be removed.

I claim:

1. A yarn package holding and securing mechanism comprising, an axially movable shaft, a support for said shaft, a yarn package core securing means being axially compressible and transversely expansible and positioned about said shaft, said securing means being adapted when transversely expanded to hold and secure said core to said shaft, adjustable means about said shaft for adjustably locating said compressible and expansible means, and cam means reacting against said support for transversely expanding said compressible means against the inner wall of said core.

2. In a creel, a stationary support for a yarn package, a longitudinally movable shaft in said support, a cam means positioned exteriorly of said support for moving said shaft, a resilient core securing means positioned about said shaft adapted upon axial compression to expand in a transverse direction, sleeves about said shaft for locating said resilient means on the shaft and for providing reaction when said resilient core se-

curing means is compressed by said cam means, and a compressible element about said shaft against which said resilient core securing means is compressed.

3. In a creel, a stationary support for a yarn package, an axially movable arbor in said support, a cam means positioned exteriorly of said support and being attached to one end of said arbor, said cam means by pivoting on said arbor and against said support being adapted to axially move said arbor, an axially compressible and transversely expansible core securing means positioned about said arbor, adjustable sleeves about said arbor for locating said transversely expansible core securing means and for providing reaction for the axial compression of said transversely expansible core securing means, and a compression spring about said arbor for op-

5

10

15

posing the axial movement of said arbor and for predetermining the axial compression and transverse expansion of said expansible core securing means.
